INVENTOR:

TSUNAJIRO KOBATAKE

BY ATTY:

Edward M. Kojima

UNITED STATES PATENT OFFICE.

TSUNAJIRO KOBATAKE, OF LOS ANGELES, CALIFORNIA.

SANITARY TOILET-SEAT PAD.

Application filed September 28, 1927. Serial No. 222,486.

This invention relates to an improved sanitary, pad for toilet seats, and the object is to produce a device of this character having a base member adapted to be secured to the 5 toilet seat, and having thereon a plurality of coverings detachably secured thereto, which will afford to each individual user a sanitary cover for the seat.

To attain these advantages, I provide a 10 base member formed from heavy cardboard, and conforming in general with the contour of the toilet seat, and having thereon a pad of sanitary sheets detachably secured to the base member, and formed so that they may 15 be readily detached from one another. I further provide the base member with a gummed surface, whereby it is quickly applied for use, and will be rigidly retained in relation to the toilet seat, and as an additional securing means, I provide interlocking and slotted flaps which, having the gummed surface, will 20 also adhere to the toilet seat.

In the drawings, I show a preferred embodiment of this invention, but it is to be understood that minor changes and modifications may be made without departing from the spirit of the invention.

In the drawings, Figure 1 is a plan view of the pad embodying my invention, the flaps of 30 the base member being shown in dotted lines in the folded and interlocked position. Fig. 2 is a plan view of the base member showing the interlocking flaps in the extended position before folding them. Fig. 3 is a sectional view of the pad applied to a seat cover. Fig. 4 is a side or edge view of the pad, with 35 the flaps shown at an angle with the base.

Referring to the drawings, the device consists of a pad 11, of suitable paper, each having a tab 12, adapted to be grasped by the 40 user when the sheet is to be detached from the pad. The tabs are arranged so that the uppermost one will always project over those beneath, thereby rendering detachment of the uppermost sheet to be readily accomplished. The pad is attached to the base member 13, which is made from extra heavy cardboard, having gummed surfaces, by which 45 it will readily adhere to the toilet seat 14,

the gummed surfaces preventing displacement relative to the toilet seat. The base member 13, has slotted outer flaps 15 and inner flaps 16, arranged so that, when folded beneath the toilet seat, they will interlock with one another, each outer flap being opposed to a corresponding inner flap. 50

In attaching the device to a toilet seat, the flaps are passed under the same, and the slotted flap extremities are placed in interlocked position. The gummed surfaces of the base 55 and flaps will adhere to the seat.

In use, each individual sheet may be detached as desired. The sheets may be made of any suitable material, but are preferably of a thin and water-proof paper fabric. The 60 tabs 12 are so formed as to prevent tearing of the sheet when it is detached from the pad. The pad 11 is made up in the manner of any ordinary pad. In replacing the pad, the base member is thoroughly moistened, and is then 65 readily removed from the toilet seat. A new pad may then be placed in position and secured to the seat. The base member has been described as constructed from heavy cardboard, but it is to be understood that gummed 70 cloth may be used as a substitute therefor and as the equivalent thereof. 75

I claim:

1. A sanitary toilet seat cover pad, comprising a base member having gummed surfaces to adhere to a toilet seat, slotted securing flaps adapted to pass under the seat, interlocking extremities on the opposed flaps, and a pad of detachable sheets secured to the base member. 80
2. A sanitary toilet seat pad, comprising a base member, gummed surfaces on the base member adapted to adhere to a toilet seat, flaps integral with the base member and adapted to pass under the toilet seat, said 85 flaps being arranged in opposed relation one to another on the base member, interlocking extremities on the flaps, and a pad of detachable sheets mounted on the base member. 90

In testimony whereof I hereunto affix my 95 signature.

TSUNAJIRO KOBATAKE.
